FRANK C. MEYERS AND HANS S. OBERNDORFER, OF CINCINNATI, OHIO.

ADVERTISING DEVICE.

Application filed July 19, 1926. Serial No. 123,427.

Our invention relates to advertising devices in general and particularly to a string or web dispensing device having incorporated with it, an alarm adapted to be set off coincident with the dispensing of the string or twine.

It is the object of our invention to provide an exceedingly simple dispensing container which has connected with it a spool or pulley, over which the string or web is guided, which spool or pulley is operatively connected with an alarm which will be actuated as the string or web is dispensed. In the preferred embodiment illustrated, it is our object to provide a string dispensing device having a pulley over which the string passes as it is dispensed, and to associate with the pulley a set of clappers which will, with the rotation of the pulley, strike against the walls of a bell or other suitable alarm.

The object of the alarm will be to attract the attention of customers to the advertising matter which will be prominently displayed on a part of the wrapping material dispensing container.

Modifications which may be used to replace the bell as an alarm may be either mechanically or electrically operated, and one specific modification which incorporates the same broad idea, and which is disclosed in our co-pending application Serial #140,137, filed Oct. 7, 1926, combines a light connected with a battery which is switched on with the operation of the switch, and which light shines through a transparency through which a moving figure, mechanically operated by a connection with the spool, may also be observed.

Referring to the drawings in which we have disclosed the advertising device in its simplest form:

Figure 1 is a side elevation of the string dispensing container.

Figure 2 is partial elevation from a different position with a portion of the container shown in section.

Generally indicated at 1 is the container which in the illustration shown is of circular shape with a top 2 through which the string is guided through a hole 3. The cylindrical container has a handle 4 shaped as a bail by which the container may be suspended if desired. In the particular bail illustrated, there are two loops, a loop 5 by which the bail may be suspended over a nail or by means of a cord, and a loop 6 which acts as a guide for the string as it is dispensed from the container. From the guiding loop 6 the string which is indicated at 7 passes about the periphery of a spool 8 mounted on a pin 9 soldered to the side of the container. Extending from an end of the spool are two clapper rods 10, which with the rotation of the spool, strike against bells 11 which are loosely mounted on a rod 12, which is also soldered to the container.

As the string is dispensed, the spool will turn and the clappers will strike against the bells, thereby calling the attention of customers to an advertisement such as may be painted on the container, and as is indicated at 13 in the drawings.

Modifications in structure will readily occur to those skilled in the art, but in so far as such modifications incorporate mechanical equivalent elements, we consider such changes to be within the scope of our invention.

Having thus described our invention what we claim as new and desire to secure by Letters Patent is:—

A string dispenser comprising a container for string, a supply of string, a guide for said string from the container to a dispensing position, a rotatable member disposed in the path of said string about which said string is looped and an alarm operatively connected with said rotatable member, said alarm comprising at least one bell, and clappers carried by said rotatable member adapted to strike said bell.
